Patented Apr. 13, 1915.

FIG. 1.

Fig. 5.

A technical line drawing of a mechanical assembly. At the top, the text '23 17 13 11 FIG. 2.' is written above a horizontal line. Below this line, the drawing shows a rectangular frame with a central circular component. Various parts are labeled with numbers: '23' is on the left side; '17' is on the top left; '13' is on the top center; '11' is on the top right; '4' is on the top right pointing to a small part; '8' is on the top right pointing to a larger part; '10' is at the bottom center; '12' is at the bottom right; and '14 16' is at the bottom left. The drawing is a black and white technical sketch.

UNITED STATES PATENT OFFICE.

HUGH A. FAULKNER, OF BURKMERE, SOUTH DAKOTA.

MAGAZINE-HAMMER.

1,135,784.

Specification of Letters Patent. Patented Apr. 13, 1915.

Application filed May 9, 1914. Serial No. 837,479.

To all whom it may concern:

Be it known that I, HUGH A. FAULKNER, citizen of the United States, residing at Burkemere, in the county of Faulk and State 5 of South Dakota, have invented certain new and useful Improvements in Magazine-Hammers, of which the following is a specification.

My invention relates to improvements in 10 hammers, and as its primary object aims to provide a tack hammer of the magazine type having feeding and delivery mechanism associated therewith.

The invention as a further object contem- 15 plates mechanism such in its nature as to feed successively, the tacks acted upon, to the delivery mechanism, the latter mecha- nism being manually operable to deliver the tacks, one at a time, into final position 20 against the head of the hammer.

The above and additional objects are accom- 25 plished by such means as are illustrated in their preferred embodiment in the accom- panying drawings, described in the follow- 30 ing specification and then more particularly pointed out in the claims which are append- ed hereto and form a part of this applica- 35 tion.

In describing my invention in detail refer- 40 ence will be had to the accompanying drawings wherein like characters designate like or corresponding parts throughout the several views, and in which:

Figure 1 is a longitudinal sectional view 45 of the hammer device, portions thereof being shown in elevation; Fig. 2 is an enlarged section on the line 2—2 of Fig. 1; Fig. 3 is a section on the line 3—3 of Fig. 2; Fig. 4 is a detail perspective view of the delivery 50 mechanism; and Fig. 5 is a fragmentary view illustrating the formation of one of the feeding tube terminals.

Referring now to the drawings by numer- 55 als, 1 designates the hammer handle and 2 the head, the former being hollow and closed at one end, the said closed end forming an abutment for one end of a spring 3 arranged therein. The opposite end of the handle 1, at a point adjacent the hammer 60 head 2 is open, as indicated at 4, said open- 65 ing forming a passage way through which the tacks or small nails acted upon are suc-

cessively fed in a manner to be hereinafter fully described.

Within hollow handle 1 a feed tube 5 is ar- 55 ranged, said tube extending from the closed end of the handle to a point adjacent the opening 4 and having arranged therein a suitable disk or plate 6 against which the opposite end of the spring 3 abuts. Tube 60 5, as illustrated in Fig. 2, is constricted as at 7 to form an auxiliary tubular extension 8 within which the head of the tacks acted upon are fitted, the shanks of the said tacks extending through the constricted portion 7 65 of the tube, preferably as shown in the said Fig. 2, the auxiliary tube 8 serving as a guide for the said tacks and maintaining the same in proper position to be acted upon by the delivery mechanism as will appear 70 hereinafter. Auxiliary tube 8 extends be- 75 yond the feed tube 5, said auxiliary tube be- ing curved to pass through the opening 4 as indicated at 9 terminating at a point be- 80 neath the hammer head and adjacent the 85 striking surface thereof.

Pivoted as at 10 to the curved extension 80 of auxiliary tube 9, is a retaining element 85 designated as an entirety by the numeral 11, said element forming an abutment for the tacks acted upon to hold the said tacks against movement by reason of the pressure brought to bear thereupon through the in- strumentality of spring 3. Element 11 is 90 shaped as illustrated in Fig. 2 to form ex- 95 tensions overlapping the slot 12 formed in the auxiliary tube, the said extensions being provided with beveled edges designated re- spectively 13 and 14. Said element 11 is 100 oscillated upon its pivot point 10 to provide for the passage of the tacks, the tacks acted upon first engaging bevel edge 13, in which event said element 11 is oscillated in the op- 105 posite direction and the tacks made to en- gage bevelled edge 14, in which position said 110 tacks are so arranged relatively to the de- livery mechanism as to be automatically car- 115 ried into final position against the striking 120 surface of the head. Said delivery mecha- nism in its preferred embodiment comprises 125 a suitable frame 15 arranged to straddle the 130 hammer head 2, said frame being pivoted as at 16 to the said head. An extension 17 135 is integral with the frame, said extension

having attached as at 18 to its free end, a rod 19, said rod being attached at its opposite end as indicated at 20 to an operating lever 21 pivoted as at 22 exteriorly of the handle 1 preferably at a point intermediate the opening 4 and the closed end of the handle. A spring 23 is also secured at one end to the extension 17, the opposite end of the spring being made fast to the hammer head 10. 2. Spring fingers 24, disposed in parallel spaced relation, are secured to the frame 15 and upon actuation of said frame, moved into engagement with the shank of the tack acted upon, the engagement between the said spring fingers and the said tack serving to grasp the latter in a manner sufficiently firm to hold and carry the said tack into final position as indicated by the dotted lines in Fig. 1. An arm 25 is also secured in any 20 suitable manner to the frame 15, said arm terminating in a head portion 26 movable, upon actuation of the delivery mechanism into engagement with the head of the tack acted upon as shown in Fig. 3, said head, 25 together with the fingers 24 firmly holding the tack until forced home by a blow delivered through operation of the hammer. The free end of auxiliary feed tube 9 is slotted as indicated at 27, said slot forming 30 a way within which arm 25 operates to provide for the arrangement of the head 26 over the head of the tack acted upon, while the slot 12 is widened at a point adjacent the slot 27, preferably as indicated at 28 to 35 provide for the operation of the spring fingers 24.

Operation is substantially as follows: Feed tube 5 is first filled with the tacks to be acted upon, the said tube when being 40 filled, causing spring 3 to be compressed. Tension of said spring 3 is sufficient to deliver the tacks successively against retaining element 11. Oscillation of said element in one direction will provide for the engagement of the said tacks, one at a time, with the beveled edge 13 of the said element and, upon oscillation of the element in the opposite direction, the beveled edge 14; the same being returned then to its normal position, 45 50 serves as an abutment for the next tack to be acted upon, thereby holding the said tack in a position ready to be subsequently moved into final position through continued or subsequent oscillation of element 11. The 55 tack acted upon having been moved into the position indicated in Figs. 2 and 3, operating lever 21 is actuated moving frame 15 about its pivot point 16 and spring fingers 26 and arm 25 into engagement therewith. 60 Said frame 15 when actuated, will swing the tack acted upon into the position indicated in Fig. 1, in which position a blow upon the head thereof will provide for the driving of the tack in a manner common to the art.

The finger 24 being highly resilient, it is 65 evident that the same may be withdrawn from engagement with the head of the tack, the latter having been partially driven into the material acted on so that the outward pull, necessary to disengagement of the tack 70 and fingers, would not dislodge the former.

From the foregoing, taken in connection with the accompanying drawings it is apparent that the feeding mechanism is automatic in its operation; that spring 23 automatically moves fingers 24 and arm 25 into engagement with the tack to be driven, the same having been moved into final position by actuation of element 11; and that by the operation of lever 21, frame 15 is swung 80 into the position indicated by the dotted lines in Fig. 1.

In reduction to practice, I have found that the form of my invention, illustrated in the drawings and referred to in the above 85 description, as the preferred embodiment, is the most efficient and practical; yet realizing that the conditions concurrent with the adoption of my device will necessarily vary, I desire to emphasize the fact that various 90 minor changes in details of construction, proportion and arrangement of parts may be resorted to, when required, without sacrificing any of the advantages of my invention, as defined in the appended claims. 95

Having thus fully described my invention, what I claim as new and desire to secure by Letters Patent, is:—

1. In a magazine hammer, a hammer head, a handle therefor, a delivery frame pivoted 100 to the hammer head, an extension mounted on the frame, spring fingers carried by the frame, said extension and said fingers being engageable with the tacks acted upon one at a time, means operable from a point on the 105 hammer handle to oscillate the delivery frame, said extension and the said fingers adapted to carry the tacks one at a time into a position to be struck by the hammer head, spring means operating automatically to return the frame into engagement with the successive tacks acted upon, and means comprising an oscillatable plate movable to successively position the tacks acted upon, for engagement with said extension and said 115 fingers, as and for the purpose set forth.

2. In a magazine hammer, a hammer head, a handle therefor, feeding mechanism comprising an oscillatable plate, means operating to move the tacks one at a time into engagement with said plate, said plate being oscillatable to move the tacks one at a time out of engagement therewith, a delivery frame pivoted to the hammer head, an extension mounted on the said frame, spring 120 fingers disposed adjacent the said extension, spring means affixed to the delivery frame, said spring means operating automatically to

force said extension and said spring fingers into engagement with the tacks moved beyond said plate, and means actuatable from a point upon the hammer handle to move 5 the said delivery frame upon its pivot point and to position the tacks one at a time into engagement with the striking surface of the hammer head, the spring fingers providing for a release of the tacks, the spring 10 means aforesaid providing for a return of

the extension and said fingers into engagement with the next tack acted upon, as and for the purpose set forth.

In testimony whereof I affix my signature in presence of two witnesses.

HUGH A. FAULKNER.
